CLAIM

The ornamental design for a floating lap desk, as shown and described.

DESCRIPTION

FIG. 1 is a perspective view of a floating lap desk; FIG. 2 is a front elevational view thereof; FIG. 3 is a rear elevational view thereof; FIG. 4 is a left-side elevational view thereof; FIG. 5 is a right-side elevational view thereof; FIG. 6 is a top plan view thereof; FIG. 7 is a bottom plan view thereof; FIG. 8 is a perspective view of the desk with cords unattached; FIG. 9 is an enlarged perspective view of the floating lap desk of FIG. 1; and, FIG. 10 is an enlarged perspective view of the floating lap desk of FIG. 8.

The cables and the desk have been shown separately in FIGS. 9 and 10 to show aspects of the design that may not be apparent in the other views.

The broken lines in the drawings show environment and form no part of the claimed design.
